(57) **CLAIM**

The ornamental design for a box for converter, as shown and described.

DESCRIPTION

FIG. 1. is a front perspective view of the front, right, and top sides of a box for converter showing our new design;

FIG. 2. is a rear perspective view of the rear, left, and bottom sides thereof;

FIG. 3. is a front view thereof;

FIG. 4. is a rear view thereof;

FIG. 5. is a top plan view thereof;

FIG. 6. is a bottom plan view thereof;

FIG. 7. is a right side view thereof;

FIG. 8. is a left side view thereof;

FIG. 9. is a first reference view showing usage state thereof; and,

FIG. 10. is a second reference view showing usage state thereof.

The broken lines shown represent portions of the box for converter and form no part of the claimed design.

The box for converter is a fuse box for converter.

1 Claim, 10 Drawing Sheets
